B. A. NOVAK

2,663,793

EXTENSION LIGHT

Filed June 13, 1951

INVENTOR

Ben A. Novak

BY

John Patterson, Jr.

ATTORNEY

clamping band transversely thereof, the ears of said neck having openings therein in registry with said screws and of greater diameter than the latter to loosely receive the same, a contractile spring extending partially around said neck, links pivoted at their inner ends to the outer extremities of said spring, said links being of greater transverse width than the ears of said neck and clamping band and adapted to engage over the same, and metal clips pivotally secured to the outer ends of said links; said links adapted to engage with the ears of said clamping band when said spring is expanded and to lock under tension of said spring with said clamping band ears.

BEN A. NOVAK. 15
